UNITED STATES PATENT OFFICE.

JOHN W. LATTA, OF LECOMpte, LOUISIANA, ASSIGNOR OF ONE-HALF TO JOHN C. BARNES, OF LECOMpte, LOUISIANA.

SWITCH-LUG.

1,102,931.

Specification of Letters Patent.

Patented July 7, 1914.

Application filed February 4, 1914. Serial No. 816,432.

To all whom it may concern:

Be it known that I, JOHN W. LATTA, a citizen of the United States, residing at Lecompte, in the parish of Rapides and State of Louisiana, have invented new and useful Improvements in Switch-Lugs, of which the following is a specification.

The present invention relates to improvements in adjustable switch lugs, the primary object being to provide a device of this character whereby all the slack between switch points may be successfully taken up.

A further object of the invention is the provision of a device of this character wherein the bridle rod or the connecting rod for the switch points may be adjusted between the said points and effectively retained in such adjusted position.

Other objects and advantages of the device will appear as the nature of the invention is more fully understood, reference being had to the accompanying drawings in which there is illustrated a simple and preferred embodiment of the improvement reduced to practice.

In the drawings: Figure 1 is a view illustrating my improvement in applied position between two railway switch points, Fig. 2 is an enlarged detail perspective view of the lug and bridle rod, the cap or cover for the body of the lug being raised above the said body, Fig. 3 is a central longitudinal sectional view through the device illustrated in Fig. 2, the cap being shown in place upon the body, Fig. 4 is a top plan view of one of the lugs, the cap or top as well as the adjustable plate being removed, Fig. 5 is a transverse sectional view on the line 3—3 of Fig. 3, Fig. 6 is a detail perspective view of the adjustable lugs, and Fig. 7 is a top plan view of a lug having its body or box portion of a different interior formation and showing an adjustable plate therein.

Referring now to the drawings in detail, the main rails are indicated by the reference characters R—R, and the switch points by the characters S—S. Secured to the inner face of each of the switch points S is a lug, which is broadly designated by the numeral 1. The lug includes a longitudinally extending attaching plate 2 which has its inner face shaped to conform to the fishing space of each of the switch rails, to be snugly received therein, each of the said plates 2 being provided with openings 3 for the recep-

tion of securing elements in the nature of the ordinary bolts and nuts for the bolts. Integrally formed with each of the attaching plates 2 approximately central thereof, and preferably at the lower corner of the plate is a transversely arranged arm 4, the said arm being inclined downwardly with relation to the said plate 2. Formed with the arm 4 is what I term the body 5 of the lug. This body is in the nature of a box or receptacle, having an open upper face which provides the same with an interior compartment 6. The lower face of the box is formed with a substantially rectangular channel 7 which extends entirely through the body below the arm 4 and below the lower wall of the compartment 6. The channel 7 is adapted to receive the end of the cross sectionally rectangular bridle or switch point connecting rod 8, the said rod being provided with one or more openings 9, while the lower wall of the channel is formed with an elongated opening 10 which registers with the said opening 9. Arranged within the compartment 6 to fully close the same is what I term an adjustable plate 11. This plate frictionally engages with the walls of the compartment 6, and the said plate is provided with any desired number of spaced openings 12, the said openings, or rather the portion of the plate upon which the openings are arranged being spirally arranged with relation to the plate 11, so that one of the openings will at all times register with the opening 9 and the elongated opening 10 in the body, and receive the shank of a bolt 13 which passes through the registering openings and above the body. The body of the lug has its open face preferably arranged below the arm 4, so that the juncture of the arm with the body provides a vertically straight longitudinally extending shoulder 14, and the upper face of the body to the end thereof opposite that provided with the shoulder 14 is formed with upwardly oppositely disposed lugs 15—15. The numeral 16 designates the closure for the compartment 6, and the said closure is shaped to correspond with the shape of the body and is provided with oppositely disposed depressions which are adapted to receive the lugs 15, while the inner edge of said closure 16 abuts with the shoulder 14. The closure 16 is also provided with an elongated opening 18, and through this 110

opening projects the stem of the bolt 13, the nut 19 for the bolt resting upon the upper face of the closure 16.

With such an arrangement, it will be noted that by removing the adjustable plate 11 to position any of the openings 12 either toward the side of the compartment 6 opposite the lug 14, or to position the said adjustable plate so that the said opening 12 which was formerly arranged adjacent the shoulder 14 is disposed to the opposite side of the compartment, the bridle rod 8 may be adjusted as desired, the adjustment just referred to being the greatest permitted, it being understood that any of the said openings arranged spirally of the plate may receive the bolt 13, so that the bridle rod may be adjusted to a nicety. In the preferred construction, the compartment 6 is of an octagon shape, and the perimeter of the plate 11 is provided with eight faces but if desired, the plate 11 may be in the form of a disk, as illustrated in Fig. 7 of the drawings.

From the above description, taken in connection with the accompanying drawings, the simplicity of the device as well as the advantages thereof will, it is thought, be perfectly apparent to those skilled in the art to which such invention appertains without further detailed description.

Having thus described the invention, what I claim is:—

1. A lug of the class set forth, including a body provided with a compartment, a bridle rod having an opening passing through the compartment, an adjustable plate having spirally arranged openings within the compartment and frictionally engaging the walls thereof, and a bolt passing through the bridle rod, the lug and one of the openings in the adjustable plate.

2. In a device for the purpose set forth, a lug including an attaching plate, an arm arranged angularly of the plate, a body connected with the arm, said body having a compartment, a removable plate having spirally arranged openings within the compartment and frictionally engaging the walls thereof, a bridle rod, and a bolt passing through one of the openings of the plate and connected with the bridle rod.

3. In a device for the purpose set forth, a lug, said lug including an attaching plate, a body connected with the plate, said body having a compartment, the body being pro-

vided with a passage which intersects the compartment, the lower wall of the passage having an elongated opening, a bridle rod having an opening arranged within the passage, a removable plate within the compartment, said plate having spaced openings, certain of which being arranged nearer the center of the plate than the remaining openings and all of the said openings being spaced at different distances from the periphery of the plate, one of said openings adapted to register in the opening provided by the channel with the opening in the rod, a cover for the compartment, said cover having an opening which is adapted to align with the registering openings, a bolt passing through the registering openings, a nut for the bolt, said nut adapted to engage with the closure.

4. A lug for the purpose set forth including an attaching plate, an angular arm connected with the plate, a body formed upon the arm and having its upper open face disposed below the arm to provide a shoulder between the said body and arm, the said body being further provided with an upstanding lug, the body being provided with a channel communicating with the interior of the body, the said channel being provided with an elongated opening, a bridle rod being disposed in the channel to fully close the channel and to have its opening register with the opening provided in the channel, a removable plate filling the compartment of the body, said plate being provided with spaced openings, each of the said openings being arranged upon the plate at varying distances from the perimeter of the plate and one of the openings adapted to register with the openings in the bridle rod and the channel, a closure adapted to abut with the shoulder having depressions to receive the lugs of the body, said closure having an elongated opening which communicates with the registering openings in the plate, bridle rod and channel, a bolt passing through the registering opening, a nut for the bolt, said nut adapted to engage with the outer face of the closure.

In testimony whereof I affix my signature in presence of two witnesses.

JOHN W. LATTA.
